(57) **CLAIM**

The ornamental design for a food carton, as shown and described.

DESCRIPTION

FIG. 1 is a front perspective view of a first embodiment of a food carton in a closed position, according to my design; FIG. 2 is a front view of the food carton of FIG. 1; FIG. 3 is a rear view of the food carton of FIG. 1; FIG. 4 is a right side view of the food carton of FIG. 1; FIG. 5 is a left side view of the food carton of FIG. 1; FIG. 6 is a top view of the food carton of FIG. 1; FIG. 7 is a bottom view of the food carton of FIG. 1; FIG. 8 is a perspective view of the food carton of FIG. 1, in an open position;

FIG. 9 is a front perspective view of a second embodiment of a food carton in a closed position, according to my design; FIG. 10 is a front view of the food carton of FIG. 9; FIG. 11 is a rear view of the food carton of FIG. 9; FIG. 12 is a right side view of the food carton of FIG. 9; FIG. 13 is a left side view of the food carton of FIG. 9; FIG. 14 is a top view of the food carton of FIG. 9; FIG. 15 is a bottom view of the food carton of FIG. 9; FIG. 16 is a perspective view of the food carton of FIG. 9, in an open position;

FIG. 17 is a front perspective view of a third embodiment of a food carton in a closed position, according to my design; FIG. 18 is a front view of the food carton of FIG. 17; FIG. 19 is a rear view of the food carton of FIG. 17; FIG. 20 is a right side view of the food carton of FIG. 17; FIG. 21 is a left side view of the food carton of FIG. 17; FIG. 22 is a top view of the food carton of FIG. 17; FIG. 23 is a bottom view of the food carton of FIG. 17; FIG. 24 is a perspective view of the food carton of FIG. 17, in an open position;

FIG. 25 is a front perspective view of a fourth embodiment of a food carton in a closed position, according to my design; FIG. 26 is a front view of the food carton of FIG. 25; FIG. 27 is a rear view of the food carton of FIG. 25;

(Continued)

FIG. 28 is a right side view of the food carton of FIG. 25; FIG. 29 is a left side view of the food carton of FIG. 25; FIG. 30 is a top view of the food carton of FIG. 25; FIG. 31 is a bottom view of the food carton of FIG. 25; and, FIG. 32 is a perspective view of the food carton of FIG. 25, in an open position. The broken lines shown in the drawings illustrate portions of food carton that form no part of the claimed design.
